(57) **CLAIM**

The ornamental design for a cellular phone case, as shown and described.

DESCRIPTION

FIG. 1 is a rear, right-side, and top perspective view of a cellular phone case showing our new design.

FIG. 2 is a rear, left-side, and top perspective view thereof.

FIG. 3 is a top plan view thereof.

FIG. 4 is a bottom plan view thereof.

FIG. 5 is a rear, right-side, and bottom perspective view thereof.

FIG. 6 is a rear, left-side, and bottom perspective view thereof.

FIG. 7 is a left-side view thereof.

FIG. 8 is a right-side view thereof.

FIG. 9 is a rear view thereof.

FIG. 10 is a front, left-side, and top perspective view thereof.

FIG. 11 is a front, left-side, and bottom perspective view thereof.

FIG. 12 is a front, left-side, and top perspective view thereof with an environmental cellular phone within the case.

FIG. 13 is a front, right-side, and top perspective view thereof.

FIG. 14 is a front view thereof.

FIG. 15 is a front, left-side, and bottom perspective view thereof; and,

FIG. 16 is a front, right-side, and bottom perspective view thereof.

The broken lines in FIGS. 1-2, 4-7, 9, and 12-16 depict an environmental cellular phone that forms no part of the claimed design.

1 Claim, 14 Drawing Sheets
